UNITED STATES PATENT OFFICE.

SIMEON LORD AND WILLIAM HENRY DAILEY, OF ST. LOUIS, MISSOURI.

INLET-NOZZLE FOR STAND-PIPES.

SPECIFICATION forming part of Letters Patent No. 315,521, dated April 14, 1885.

Application filed July 7, 1884. (No model.)

To all whom it may concern:

Be it known that we, SIMEON LORD and WILLIAM HENRY DAILEY, of St. Louis, Missouri, have jointly made a new and useful Improvement in Stand-Pipes, of which the following is a full, clear, and exact description, reference being had to the annexed drawings, making part of this specification, in which—

Figure 1 is a side elevation of a stand-pipe having the improvement; Fig. 2, a longitudinal section on the line 2 2 of Fig. 3; Fig. 3, a longitudinal section on the line 3 3 of Fig. 2, and Fig. 4 a cross-section on the line 4 4 of Fig. 2.

The same letters of reference denote the same parts.

The present invention is an improvement in that class of stand-pipes having two or more inlets and a valvular mechanism, enabling the water to be delivered into the stand-pipe through either or both of the inlets, but preventing the water, when introduced through but one of the inlets, from being discharged through the other of the inlets. Such stand-pipes are frequently attached to the outer walls of buildings for the purpose of carrying streams of water to the upper part of the building.

The improvement relates to the valve and the mechanism therewith immediately connected.

A, Figs. 1, 2, 3, represents that portion of the stand-pipe with which the improvement is immediately associated. B B' represent the two inlets thereto. G represents the valve. In place of employing a flap-valve, one for each inlet, we use a single ball-valve. This valve is adapted to seat either at b or at b', according to the direction in which the water is introduced into the stand-pipe. If water is introduced through the inlet B, the valve will be forced by the water to seat at b' at the top of the inlet B', and thereby prevent the water from escaping downward through the inlet B'. If, on the other hand, the water is delivered into the

stand-pipe through the inlet B', the valve is lifted from its seat b' and caused by the water to seat at b at the top of the inlet B. The guard D prevents the valve from rising too high in the stand-pipe, and it also directs the movement of the valve as it is transferred to and from the seats b b', as described. In case the water is being delivered into the stand-pipe through both of the inlets B B' at the same time, the valve is lifted, and is upheld in the chamber a above the seats b b'; and to steady the valve at such time, so that it shall not interfere with the admission of the two streams of water, and so that it shall be in position to drop readily to the seat b or b', according to the flow of water, as described, the guard, in addition to being curved upward in the chamber a, is extended upward at its center to form a pocket, d, into which the ball is received, as indicated by the broken lines C', Figs. 2, 3. In this manner, and by using the valve as described, there is no liability of the valvular mechanism getting out of order, as is liable to be the case when a flap-valve is used.

We claim—

1. The combination, in a stand-pipe, substantially as described, of the chamber a, the inlets B B', having, respectively, the valve-seats b b', the ball-valve C, and the guard D.

2. The combination, substantially as described, of the chamber a, the inlets B B', having, respectively, the valve-seats b b', the ball-valve C, and the guard D, curved upward in the chamber.

3. The combination, substantially as described, of the chamber a in the pipe, the inlets B B', having, respectively, the valve-seats b b', the ball-valve C, and the guard D, curved upward, and also having the pocket d.

SIMEON LORD.

WILLIAM HENRY DAILEY.
